UNITED STATES PATENT OFFICE

ALLISON J. THOMPSON, OF CLEVELAND, OHIO

SHOCK ABSORBER FOR INVERTED LAMPS

Application filed January 16, 1928. Serial No. 247,066.

This invention relates to the type of lamp fixture adapted to support an incandescent electric lamp in inverted position, that is with the lamp bulb portion upstanding from the base portion thereof as distinguished from the more customary pendent relation of bulb portion to base portion; and more particularly the invention pertains to the provision in such a fixture of means for saving the lamp from the destructive effect of shocks and jars which might otherwise be transmitted thereto from the fixture supporting means.

In the usual electric lamp installation the normal position of the lamp is pendent, that is, the fixture is arranged with the lamp receiving socket opening downwards, whereby a lamp in the socket is positioned with its bulb portion below its base portion. Where shock absorbing means are to be provided in such an installation it is a relatively simple matter to support the lamp receiving base portion of the fixture upon spring means, since the center of gravity of the lamp and base assembly falls naturally below the most convenient point of attachment between the assembly and the spring means.

Where the lamp is to be in upstanding or inverted position however, the mass of the lamp is over the center of gravity of the lamp and bulb assembly, whereby stabilizing means must be provided in addition to merely resilient means for the purpose of maintaining such a lamp position. According to my invention I employ a counter-weight which serves as the necessary stabilizing means, lowering the center of gravity of the lamp and base assembly, which assembly now also embraces the stabilizing means, so that the most convenient point of attachment between assembly and spring lies naturally above the center of gravity. Also, owing to its weight such stabilizing means increase the mass of the assembly and so add to its inertia properties as to greatly increase the vibration absorptive effect of the spring.

Briefly the principal object of the invention therefore is to provide shock absorbing means in an inverted lamp installation.

The invention is particularly applicable to so-called street series lamps for highway

illumination. In such installations, where the lamp is supported in elevated position from a pole located at the side or center of the street, the vibration of continuous traffic passing the pole is transmitted through the pole and multiplied thereby so that not only is the filament life ordinarily much shortened, but also frequent breakage occurs in the globe enclosing the lamp.

A further object of my invention is to so arrange my shock absorbing means that not only the lamp, but also the enclosing globe therefor, is shock insulated, so to speak, from the supporting pole.

Further objects and advantages of the invention will be apparent from the following description taken in connection with the accompanying drawings in which Fig. 1 is a side elevation of a street series installation, parts of the fixture being shown in section for the purpose of disclosing details of construction; Figs. 2 and 3 are enlarged sectional views corresponding with the section portion of Fig. 1 and Fig. 4 is a horizontal section in the plane of line 4—4, Fig. 1; Fig. 5 is a view generally similar to Fig. 1 but showing a fixture arrangement wherein the globe as well as the lamp is protected by shock absorbing means; and Fig. 6 is a detail section of parts appearing in Fig. 5 but taken as in a vertical plane normal to that of the sectioned portion of Fig. 5.

With reference now to the drawings and particularly to Figs. 1 to 4 thereof, 1 is a supporting pole or "lamp post" having a laterally extending arm 2 upon the outer end of which is secured a hollow ornamental casing 3. The casing 3 is provided in its upper portion with an inwardly extending flange 4 upon which is seated the lower and larger terminating convolution of a bee-hive type of coil spring 5. Seated upon the upper and smaller end of the spring is a saddle 6 having at its ends downwardly turned flanges 7 fitting the spring and medially of the flanges a depressed portion 8 fitting the porcelain portion 9 of a standard "mogul" base provided with a lamp receiving socket portion 10, and having oppositely disposed terminal arms 11. The lamp base is secured with the saddle by the

usual bolts 12 and the saddle is provided on each side of the base with an opening in which is seated an insulating eyelet 13. Secured with the base as by threaded connection 14 centrally of and with the saddle 6 is a rod 15 which extends downwardly through the coils of the spring 5 to the lower portion of the hollow of the casing 3 terminating therein in a weight 16 which serves as a 10 counterbalance and stabilizing element as will appear. Surrounding the weight and within the casing is a sleeve 17 secured with the casing as by screws 18 and having a lining 19 of relatively soft material such as rubber, felt 15 or the like. Wires 20 lead from the terminal arms 11 of the base downwards through the eyelets 13 and the spring 5, and through the arm 2 and pole 1 which are of course, hollow, and to connection with the supply line.

20 The upper extremity of the casing 3 terminates with a peripheral shoulder as indicated, whereby an annular seat 21 is provided for the globe 22 for the lamp 23 turned into socket 10 of the base. Secured to the upper 25 extremity of the casing 3 as by welding at 24 is a collar 25 having for drainage purposes a number of notches 26 and carrying a number of wing nuts 27 by which the globe 22 may be removably secured with the casing 30 in the usual fashion.

35 The strength of the spring is such that the lamp, base, rod and weight, assembly will be resiliently supported thereby, and the length of the rod and size of the weight are such that the base is counterbalanced to maintain the lamp in upstanding or inverted position as indicated and clear of the lined sleeve 17 interposed between the weight and the casing. In other words the assembly is stabilized with the lamp in the desired inverted 40 position.

45 Obviously by the arrangement described the lamp is yieldably maintained in inverted position, being resiliently supported on the spring 5 and movable with swinging motion thereon to the limit of the swinging motion of the weight within the soft lining of the sleeve 17. The lamp is thus insulated directly by the spring from any vertical vibration of the arm 2, and any ordinary horizontal vibrations of the arm are absorbed by the inertia action of the described assembly seated on the spring, which yields horizontally under such conditions, and the clearance 50 of the weight within the sleeve is sufficient for such purpose. Should horizontal vibrations be excessive enough to effect contact between the weight and the lining 19, the lining is soft enough and the rod 15 long 60 enough to prevent injurious effects on the lamp filament, and the arrangement obviously limits the tilting motion of the lamp.

65 Referring now to the modification appearing in Figs. 5 and 6, in which similar parts bear similar reference numerals, the saddle

6' with which the porcelain base portion 9' is secured by bolts 8 as before, is extended peripherally about the upper extremity of the casing 3 and downwardly turned for the purpose of excluding the elements from the interior of the casing. The bottom of the casing is open as indicated and bears a liner 19' of relatively soft material. Extending from connection with the saddle 6' downwards through the casing is a tubular member 15' secured with the base by the bolts 8. The members 6' and 15' are supported on a spring 5 the upper convolution of which fits closely about the member 15' and bears against the member 6'. Through the upper hollow portion of the member 15' extend lead wires 20 which carry current to the lamp base. Secured within an upstanding flange 25' carried by the saddle 6' is a globe 22. In the lower extremity of the member 15' is a weight 16'. The weight 16' is correspondingly greater than the weight 16 as the mass of the lamp plus that of the globe is greater than that of the lamp alone.

70 It will be seen that the arrangement set forth in Figs. 5 and 6 is one wherein not only is the lamp supported on the spring 5 but the globe is also so supported and counterbalanced by the weight 16'. The functioning of this arrangement is similar to that 75 already described of the showing of Figs. 1 to 4 inclusive, with the exception of course, that the globe as well as the lamp is protected from shocks.

80 What I claim is:

1. In a lamp fixture, a fixed casing having an upper opening, a saddle adapted to carry a lamp and having a portion extending over and about said opening to protect the same from the elements, said saddle being adapted to carry a lamp and a globe therefor, means for resiliently supporting said saddle on said casing, and counterbalance means extending within said casing below said supporting means and associated with said saddle to 90 maintain said lamp and globe in upright position above said opening.

100 2. In a lamp fixture, a fixed casing, a saddle adapted to carry a lamp, means for resiliently supporting said saddle on said casing, counterbalance means associated with the saddle to maintain said lamp in upright position, and extending into said casing below said supporting means, and buffer means arranged between said casing and said counterbalance means whereby the swing of the latter is yieldably limited.

110 3. In a lamp fixture of the class described, a hollow ornamental casing, a supporting arm laterally extending therefrom, a saddle adapted to carry a lamp, means within said casing above the level of said arm for resiliently supporting said saddle on said casing, and a counterbalance mass within said 120 125 130

casing below the lever of said arm and fixedly associated with the saddle and otherwise free to move within said casing, to yieldably maintain said lamp in upright position.

5 In testimony whereof I hereby affix my signature.

ALLISON J. THOMPSON.
